HOWARD L. JOHNSTON, OF FOREST HILLS BOROUGH, PENNSYLVANIA, ASSIGNOR TO
WESTINGHOUSE ELECTRIC & MANUFACTURING COMPANY, A CORPORATION OF
PENNSYLVANIA.

LOCOMOTIVE HEADLIGHT.

Application filed January 16, 1924. Serial No. 686,542.

My invention relates to lighting fixtures and particularly to focusing devices for use in said fixtures.

My focusing device is particularly adapted for use in headlights which are subjected to unusually sever operating conditions, such as locomotive headlights. In such service, the lamp should be exactly in focus in order that it shall project the light rays in the most effective manner. The adjustment of the focus is difficult to maintain on account of the severe jars and shocks encountered in service. As focusing is an operation which the ordinary workman is not able to perform and which cannot be properly done except under special conditions, it is necessary that the adjustment be maintained at least as long as the life of the lamp element. When a new lamp is installed in the headlight, a new adjustment of the focus is usually necessary.

Another requirement of a focusing device is that it shall be capable of adjusting the lamp into a plurality of positions in the reflector aperture. This is accomplished in part, by a straight line adjustment which permits the light to be placed at any desired depth in the reflector aperture, and in part, by a ball-and-socket joint which permits a circular movement of the lamp.

It is, therefore, one object of my invention to provide a focusing device which shall be capable of universal movement.

Another object of my invention is to provide a focusing device whereby one unit of the device shall be held in temporary adjustment while the other adjustment is being made.

Still another object of my invention is to provide a focusing device in which the parts shall be securely clamped when the lamp is in exact focus in such manner that the adjusted parts shall not be displaced by reason of shocks and jars.

Heretofore, focusing means have been provided with devices which permit universal movement of the parts. Many such devices were used under conditions where the fixture was not subjected to shocks and jars, and consequently no special means for maintaining the lamp in focus was necessary. Focusing was so seldom required that no special devices were needed to facilitate the operation.

My invention provides a structure which permits the universal movement of the lamp. The parts are held temporarily in frictional engagement for adjustment, and are finally locked in position. Specifically, I provide a lamp-supporting spindle which passes centrally through a ball-and-socket joint that is capable of universal movement. The ball-and-socket joint is provided with a clamp and spring mechanism which holds it in movable frictional engagement while the spindle is being adjusted. The clamp and spindle are also provided with a plurality of lock-nuts by means of which the adjusted parts are locked in a permanent manner.

Throughout the drawing, constituting a part hereof, in which like characters designate like parts,

Fig. 1 is a view, partially in elevation and partly in cross section, of a headlight with a focusing device therein;

Fig. 2 is a cross-sectional view of the clamp taken along the line II—II of Fig. 3, and

Fig. 3 is a plan view of the clamp shown in Fig. 2.

The headlight casing 1, shown in Fig. 1, is provided with a reflector 2 and a lamp 3 therein that is mounted in a socket 4 in a well known manner. Upon one end of a spindle 5 which is supported centrally in a ball-and-socket member which has a ball portion 6 at one end and a flattened apertured portion or yoke 7 at the other end thereof. The end of the spindle 5 remote from the lamp is threaded and projects through the apertured portion 7 of the ball member.

A knurled nut 8 is mounted on the spindle in the apertured portion of the ball member for moving the lamp along the axis of the spindle in one direction. External to the apertured portion, a thumb nut 9, mounted on the spindle is adapted to move the lamp in the opposite direction, and also serves as a lock-nut for the spindle. A second thumb nut 10 is mounted on the spindle and serves as a lock-nut for the first thumb nut. A screw 11 in the ball member projects into a groove in the spindle to prevent the spindle from turning. A two-part socket is formed partly in a clamp 12 and partly in the rear wall 13 of the casing and, together with the

ball 6 fitted therein, comprises the ball-and-socket joint. The joint is held together by the clamp 12 which is hinged to a bracket 14 or clamp on the casing.

- 5 The clamp 14 is apertured and is provided with a centrally located socket portion 15 which fits over the ball 6. At diametrically opposite points 16 of the aperture, the clamp is cut away in order to allow it to be slipped 10 over the flattened apertured portion 7 of the ball member when the parts are assembled. In one end of the clamp, a countersunk opening 17 fits loosely over a bolt 18 in the casing. A thumb nut 19 screws on the bolt 18 15 against the clamp and prevents the ball from moving. A coil spring 20 around the bolt 18 bears against the clamp 14 and holds the ball-and-socket joint in temporary engagement when the thumb nut 19 is not screwed 20 down. A second thumb nut 21 is mounted on the bolt and serves as a lock-nut for the thumb nut 19.

The lamp is focused in the following manner. Starting with all the parts released, 25 the thumb nut 19 is screwed down until the spring 20 bears against the clamp 12 sufficiently to hold the ball from moving. The spring is of such strength that it allows the ball to be moved and to be retained in any 30 adjusted position. The longitudinal adjustment of the lamp is made by varying the position of the knurled nut 8 and the thumb nut 9 on the spindle 5. The spindle may be moved to very nearly the correct position 35 and held therein temporarily. The final adjustments are then made by varying the position of the ball in its socket in a well known manner. When the lamp is exactly 40 in focus, the thumb nut 19 is screwed tightly to lock the clamp in its final position, and the lock nuts 10 and 21 are screwed down.

Although I have described a specific embodiment of my invention, I do not limit it thereto, since various modifications there- 45 of will suggest themselves to those skilled in the art, without departing from the spirit of my invention, the scope of which is defined in the annexed claims.

I claim as my invention:

- 50 1. In a light projecting device, a focusing device comprising a universal joint member,

a lamp-supporting spindle axially disposed in said member and movable along its axis, a spherical portion at one end and a flattened apertured portion at the other end of 55 said member, means in said apertured portion for adjusting said spindle, means external to said apertured portion for adjusting said spindle, means for clamping said member, a nut for locking said clamping 60 means and a spring bearing against said nut and clamping means for restraining the movement of said universal joint member.

2. In a light projecting device, a focusing device comprising a socket, a ball member, 65 a clamp, a ball on one end and a flattened apertured portion on the other end of said ball member, a lamp-supporting spindle axially positioned in said ball member and slide- 70 able therein, a nut in said apertured portion for adjusting said spindle, a spindle adjust- ing and locking nut external to said aper- tured portion, a nut to lock said clamp and ball member and a spring external to said clamp bearing on said nut and clamp for 75 maintaining said ball and clamp in frictional engagement when the nut is loosened.

3. A focusing device adapted to be mounted on a lamp casing having an apertured socket in one portion thereof comprising a 80 threaded lamp spindle provided with adjusting and locking nuts mounted thereon, a sup- port for said spindle having a ball member on one end thereof adapted to be mounted in said socket and to form a closure for said 85 opening and a flattened portion having an opening therein on the other end thereof, said flattened portion being adapted to permit the operation of one of said adjusting nuts within said opening and to permit the 90 operation of other adjusting nuts exterior thereto, said support having an axial open- 95 ing therein coextensive with the opening in said casing whereby said spindle is inserted into said casing through said support, and an apertured clamp attached to said casing and adapted to lock said support and casing together.

In testimony whereof, I have hereunto 100 subscribed my name this 27th day of December, 1923.

HOWARD L. JOHNSTON.
